US0D1078365S

(12) **United States Design Patent** (10) **Patent No.:** **US D1,078,365 S**
(45) **Date of Patent:** **** Jun. 10, 2025**

(54) **INDUCTION COOKER**

(71) Applicant: **SMEG S.P.A.**, Guastalla (IT)

(72) Inventors: **Leopoldo Bazzicalupo**, Sale Marasino (IT); **Raffaella Mangiarotti**, Milan (IT); **Vittorio Bertazzoni**, Guastalla (IT)

(73) Assignee: **SMEG S.P.A.** (IT)

(**) Term: **15 Years**

(21) Appl. No.: **35/519,710**

(22) Filed: **Jan. 16, 2023**

(80) **Hague Agreement Data**

Int. Filing Date: **Jan. 16, 2023**

Int. Reg. No.: **DM/226677**

Int. Reg. Date: **Jan. 16, 2023**

Int. Reg. Pub. Date: **Jan. 19, 2024**
